MERCHANTISE CONTAINER

Charles W. Boston, Kenmore, N. Y.

Application August 5, 1933, Serial No. 683,793

2 Claims. (Cl. 217—64)

This invention relates to display containers and it has particular relation to a container adapted to display cigars, candy, or the like, in such manner that the container always appears to be full, or that the visible layer or partial layer of the article is always presented at the upper portion of the container.

One object of the invention is to provide an improved arrangement for supporting a movable bottom of a container at various positions from a lower container extremity toward its upper edges for presenting successive layers of articles in such manner as to cause them to appear to be the first layer in the container.

In selling articles, such as cigars, it has been found that customers are somewhat averse to selecting such articles from a container which is partially or almost empty because of the possibility that the articles in such container should not be fresh, or that they may have been handled by other parties. Aversions of this kind are particularly noticeable in the selling of cigars where several layers are packed in a container, and consequently, it is somewhat difficult to sell the last layers. It is not feasible to replenish the supply from a newly opened container because the federal laws are strict in regard to the use of tobacco containers upon which the federal stamp has been affixed.

In the drawing:

Fig. 1 is a perspective of a container embodying the invention, and which has portions broken away for the sake of clearness;

Fig. 2 is a fragmentary longitudinal section of the container;

Fig. 3 is a perspective of a supporting device for carrying the bottom of the container;

Fig. 4 is a fragmentary longitudinal section similar to Fig. 2 and illustrating another form of container structure;

Fig. 5 is a perspective of a supporting device for carrying the bottom of the container shown in Fig. 4;

Fig. 6 is a vertical section of one end portion of a container illustrating another form of mounting for the bottom of the container at various positions between the top and bottom of such container; and

Fig. 7 is still another form of connection between the bottom of the container and the end walls thereof.

Referring to Fig. 1, the invention is shown as embodied in a container 10 having end walls 11, upright side walls 12 and a hinged top 15. Each end wall 11 is provided with a pair of upright sup-

porting strips 16, each of which has an outwardly turned flange 17 secured to the lower edge of the end wall 11 by means of suitable fasteners 18 in the form of bolts, screws, or the like. Another right angled flange 19 of each support is bent oppositely from the flange 17 and provides means for supporting a movable bottom 20 of the container.

It has been found that the supporting strips 16 can be formed of thin material, such as metal, or the like, which has an appreciable degree of resiliency. Ordinarily the fastening devices 18 provide for sufficiently rigid assembly to maintain the supports firmly in proper position, but if desirable the faces of these supports engaging the walls of the container can be fastened to the walls either by adhesive or other fastening means.

A plurality of tongues 22 are stamped from the body of the supporting devices 16 and are spaced in aligned relation from a position adjacent the bottom of the container toward the top thereof. These tongues are so spaced as to project inwardly substantially at the division lines between several layers of articles of merchandise 25, each layer corresponding substantially to the distance between one of the tongues and the next succeeding upper or lower tongue.

In packing the container with articles 25, the bottom 20 is positioned in the container in such manner as to rest upon the flanges 19. In this position the various tongues 22 project slightly inwardly over the end edges of the bottom. Suitable layers of paper, tinfoil or the like, indicated at 26, separate the various layers of articles of merchandise and after the top layer has been sold the bottom 20 of the container is moved upwardly until the edges thereof snap over the first tongue 22 of each supporting device 16, thereby bringing the second layer upwardly to a position formerly occupied by the first layer of articles. The bottom of the box is again manipulated when the articles of the successive layers have been exhausted until the last layer of articles in the container is presented at the top of the container and the bottom of the container is supported upon the upper tongues 22 of the supporting devices 16.

Since the material of which the supporting devices are composed is somewhat resilient, the edges of the bottom can be snapped over the tongues without difficulty and these tongues are sufficiently strong to support the loads that are imposed upon them. These supporting devices are concealed entirely inside the container and hence there is no likelihood that the character

of the movable bottom of the container should be apparent to customers. Also, in view of the resilient character of the tongues 22, the bottom 20 cannot be again moved downwardly, and hence, the container cannot be refilled without disassembling and rebuilding it. It will be observed that at least two of the supporting devices 16 are disposed at each end wall of the container, and hence, there is an even distribution of weight and uniform adjustment in an upward direction as the several layers of articles are presented at the top of the container. A layer of paper 26 is provided between the lower layer of articles and the bottom of the container in order to provide the appearance that there is another layer of articles beneath that which is presented at the top of the container.

In the form of the invention shown in Figs. 4 and 5, the container 10 is constructed in the same manner as that shown in Fig. 1 with reference to its ends 11, sides 12, top 15 and bottom 20. However, a different type of supporting device 27 is provided which has an inwardly turned flange 23 secured, as indicated at 29, to the lower surface 25 of the bottom 20 and the supports are movable upwardly with the bottom. Each supporting device 27 is formed of strip material and has tongue portions 30 stamped therein, the upper end portions of which are sharpened and bent outwardly, as indicated at 32, for the purpose of engagement in a recess 33 formed in the end wall of the container adjacent the top thereof. Each of these supporting devices is also scored or weakened, as indicated at 35, from the opposite edges thereof 30 to a location defined by the lower edges of the tongues 30. Thus, a plurality of detachable sections 36 are provided in each supporting device and each of these sections can be detached by manually bending it one or more times.

After the first layer of merchandise has been exhausted from the container, the bottom 20 is moved upwardly until the upper tongues 30 of the supporting devices project above the top of the container. Then the upper section 36 is bent and detached from the support and the succeeding sharpened portion 32 of the tongue is pressed into the recess 33 provided for each supporting device. This operation is continued until the last layer of articles is presented at the top of the container.

Referring to Fig. 6, a portion of the container construction already described is shown and each end wall 11 is provided with recesses 40 for receiving the outer end of a latch 42 that has an intermediate pivotal connection 43 securing it to the bottom 20 of the container. The bottom is provided with latches at locations corresponding to the locations of the several supporting devices 16 shown in Fig. 1. The recesses 40 are spaced from the bottom to the top of the container according to the thickness of the layers of merchandise packed therein. In operating this type of bottom, each latch 42 is pivoted from one recess at a given level and the bottom 20 is moved up-

wardly to the succeeding recesses 40 for supporting the bottom at the desired level and successively presenting the layers of merchandise at the top of the container as previously described.

In Fig. 7, a similar construction to that of Fig. 6 is shown, but in this arrangement, a latch 45 is provided with a central slot 46, and a pin 47 mounted in the bottom 20 of the container extends through the slot and slidably supports the latch thereon. Recesses 48 formed in each end wall 11 of the container are adapted to receive the end portions of the latch 45 for supporting the bottom at various levels according to the thicknesses of layers of merchandise packed in the container.

Although several forms of the invention have been shown and described in detail, it will be apparent to those skilled in the art that the invention is not so limited but that various changes may be made therein without departing from the spirit of the invention or from the scope of the appended claims.

What is claimed is:

1. In a merchandise container for presenting successive merchandise layers in the top portion of the container, a movable bottom for the container, upright walls surrounding the bottom, a plurality of supporting devices composed of strip material mounted in the container, one end of the strip material of each device having portions for bending in opposite directions at right angles to the body of the strip to form flanges, one of the flanges being in the form of a tongue struck out intermediately from the body of the strip and secured to one of the lower wall portions of the container, the other flange serving as a support for the bottom, the body portion of each device having tongue portions struck out therefrom into the path of movement of the edges of the bottom in its movement from the bottom of the container toward the top of the latter, whereby the bottom is adapted to snap over the tongue portions and be supported at various elevations between the bottom and top of the container.

2. A merchandise container for presenting successive merchandise layers in the top portion of the container, a movable bottom for the container, upright walls surrounding the bottom, a plurality of supporting devices composed of strip material and mounted on the container walls for supporting the bottom, each supporting device having struck out tongue portions and having weakened portions adjacent the tongue portions to provide a structure including detachable sections, each section having a tongue portion thereon, said walls having means for receiving the tongue portions of any of the sections in mounting the latter upon said walls, whereby the bottom is supported at various elevations between the bottom and top of the container.
